UNITED STATES PATENT OFFICE.

MATTHIAS M. KANDLE, OF SPRINGFIELD, MASSACHUSETTS, ASSIGNOR TO KANDLE-BORN COMPANY, OF SPRINGFIELD, MASSACHUSETTS, A CORPORATION OF MASSACHUSETTS.

CIRCUIT-CONTROLLING DEVICE.

1,117,396.

Specification of Letters Patent. Patented Nov. 17, 1914.

Application filed November 6, 1912. Serial No. 729,713.

To all whom it may concern:

Be it known that I, MATTHIAS M. KANDLE, a citizen of the United States of America, residing at Springfield, in the county of 5 Hampden and State of Massachusetts, have invented new and useful Improvements in Circuit-Controlling Devices, of which the following is a specification.

This invention relates to a sensitive circuit controlling device and more especially to a mechanical device to control a circuit by extremely small variations in the movement of the sensitive element and the object of the invention is to provide a device of this class 10 with a sensitive element arranged to give the desired opening and closing of the circuit, and more especially the object of the invention is to provide such a device with means for readily fixing the degree of sensitiveness 15 according to conditions desired for closing and opening the circuit.

The embodiment of my invention chosen for the purposes of illustrating the same will now be described in connection with the 20 drawings, in which—

Figure 1 is a plan view of the circuit controller. Fig. 2 is a rear elevation of the same. Fig. 3 is a sectional view taken on line 3—3 of Fig. 2.

I have found this invention particularly 25 useful in its application to electrical stop motions for printing presses where it is desired to stop the press whenever a sheet to be printed is not properly fed. The invention has in the embodiment shown been mounted on a flat metal plate *a* suitably attached to the press. A block of insulating material *k* is attached to plate *a*. Within 30 a slot in the plate *a* there is mounted for rocking movement on metal pivot *h* an arm *g*. This arm can be rocked so that the front top surface thereof lies either above or below the surface of plate *a*. As shown in Fig. 3 arm *g* is at its extreme upper limit. 35 The arm is preferably struck up from sheet metal stock and has a downwardly extending flange on the short arm in the rear of pivot *h*. To this flange one end of a spring *j* is attached (see Fig. 3) the other end being 40 attached to block *k* as shown. The spring tends to turn the arm *g* above the surface of plate *a*. This turning movement can be 45 regulated or adjusted to some extent by bending the downwardly extending flange 50 toward or away from the pivot *h* where the

spring *j* will get less or more turning leverage on the arm.

Normally bearing on the rear top point of arm *g* is a spring terminal *e* pivoted in block *k* from the rod or pin *c*. Above this 55 pin and in the rear thereof is a stop pin *d* limiting the backward movement of the spring terminal *e* as shown in Fig. 3. With the terminal *e* in this position, spring *j* is free to pull arm *g* to the position shown. A 60 regulating thumb screw *b* with a wedge shaped or pointed end is mounted in front of and above stop pin *d*. When screw *b* is turned inwardly, terminal *e* is forced to its back limit and when screw *b* is 65 turned outwardly, terminal *e* moves to its front limit and at the same time forces arm *g*, since it is stronger than spring *j*, 70 downwardly due to its contacting *j* back of and above pivot *h*. Thus by adjusting 75 thumb screw *b*, the position of the outer end of arm *g* above or below plate *a* is fixed with a fine degree of adjustment.

The pivot *h* on which arm *g* is mounted is so arranged that on the least movement 80 downwardly of the outer end of arm *g* the point on the rear thereof contacting with terminal *e* immediately leaves its contacting position with *e*. While the general arrangement shown, as in Fig. 3, has been found to 85 give satisfactory results it is clear that were the normal contacting point between *g* and *e* directly above pivot point *h*, the connection would break on the smallest possible movement of arm *g* for the contacting point 90 on arm *g* would move in a perpendicular direction to the contacting surface of terminal *e*. I include such a structure in my disclosure because theoretically it would give 95 perfect results for my purpose. I find that the form shown is easier to make and gives the practical results desired. If it should be desired to get closer results, the normal contacting position for arm *g* and terminal *e* can be arranged directly over pivot *h*.

The specific operation of the circuit controlling device shown for illustration is as follows: One terminal of an electric circuit is connected by wire *m* with a binding screw 105 against which the pivot screw *C* abuts. This forms a path from binding screw to terminal *e*. The other terminal of the circuit is the metal plate *a* which is connected to arm *g* by metal pivot *h*. When the parts have 110 been adjusted as desired the edge of a sheet

of paper as fed to the printing press squares against the plate a , and forces the end of arm g level with the plate which breaks the circuit by means described. The arm g can 5 be adjusted so that if the paper does not square properly against plate a , the circuit will not be broken. This result can be used to stop the press or ring an alarm by well known arrangements.

10 While I have described my invention in its preferred form, I have done so only for purposes of illustrating the principles thereof and not with any intention of limiting the broad invention to the specific form 15 shown.

What I claim, is:

1. A device of the class described comprising in combination two terminals, one of 20 which is pivoted near its end, a spring causing said terminal to turn against the other terminal as a stop together with means comprising a threaded member formed with a tapered end portion for adjusting the last mentioned terminal and spacing it away 25 from its support to fix the angular position of the pivoted terminal, all constructed and arranged so that a pressure on the long end of the pivoted terminal will cause the short end to move away from the adjusted terminal.

2. In combination, a flat metal plate, a

circuit terminal pivoted in a slot thereof, the pivot point being adjacent one end of the terminal, a block of insulating material fastened to the plate, a spring having one end 35 fastened to the short end of the terminal and the other to the block whereby the former is turned on its pivot, a second terminal fastened at one end to the block and acting at the other end to press against the pivoted 40 terminal to turn it against its spring, and an adjusting member arranged to limit the movement of the second terminal and thereby adjust the position of the long end of the first terminal with relation to the flat 45 metal plate.

3. In a circuit controlling device, the combination, a slotted gage plate against which an article to be accurately located is placed, a contact member pivotally secured to the plate and having its free end located within the slot, a second contact member normally in engagement with the first contact member, means to adjust the second contact member to cause the first member to move relative to the face of the plate, and a spring to maintain the first member in contact with the second member.

MATTHIAS M. KANDLE.
